UNITED STATES PATENT OFFICE.

ALBERT W. THOMPSON, OF LOWELL, MASSACHUSETTS, ASSIGNOR TO PARKS-CRAMER COMPANY, OF BOSTON, MASSACHUSETTS, A CORPORATION OF MASSACHUSETTS.

PROCESS AND APPARATUS FOR CONDITIONING TEXTILE MATERIALS.

Application filed October 5, 1925. Serial No. 60,371.

This invention relates to improvements in processes and apparatus for delivering liquid to a liquid-supplying means at a predetermined uniform rate. More specifically 5 the invention relates to processes and apparatus for spraying textile fibres with oil, or other liquid, during the process of manufacture or treatment of the textile material.

The invention in its broad aspect comprises the process of delivering liquid to a liquid distributing means at a predetermined uniform rate by circulating a confined body of liquid at a rate of flow greater than the desired rate of delivery thereof, 10 maintaining by such circulation a column of liquid of uniform height, and delivering the liquid from said column to said distributing means under a predetermined hydrostatic head. 15 The invention as employed in spraying textile fibres contemplates the application of oil, or other liquid, to a given quantity of fibres in such a manner that it may be conveniently regulated and controlled with 20 close precision and may be reduced to comparatively minute quantities and rates of supply with undiminished accuracy of control.

My earlier Patent No. 1,401,376 granted December 27, 1921, discloses a method and apparatus for controlling the supply of liquids, such as oils and emulsions, to textile fibres. This type of apparatus is widely and successfully utilized in textile industries, particularly in the treatment of wool 35 preparatory to carding and spinning by woollen processes.

In ordinary practice, especially in the woollen industry, it is desirable to apply emulsion to the material to the extent of as much as thirty percent by weight and it is desired that a portion of the water composing the emulsion shall subsequently evaporate as manufacture progresses. The 40 important requirement, therefore, under such circumstances is to insure the application of an amount which shall always exceed a certain minimum. Under such circumstances precise regulation is not an important factor.

In treating cotton with oil to facilitate its manufacture the conditions are quite different. In the recently developed practice in cotton industry the oil is applied to a moving body of the raw cotton before it 55 is acted upon by the so-called "breaker lapper"—the first machine in what is known as the picking process—or by any machine which performs a similar function. The amount of cotton delivered to such machine 60 is relatively small, averaging in the neighborhood of six hundred pounds of cotton per hour, and the percent of oil desirably to be applied is also small, usually in the neighborhood of from one-half to three-fourths of one percent by weight, which corresponds approximately to an application of about one-half gallon of oil per hour.

Customarily no water is mingled with the oil since raw cotton resists absorption 70 of water. Any excess of oil impedes the proper elimination and separation of seed, leaf, and other impurities from the cotton which is the chief purpose of the picking process. Close regulation of the delivery of oil, therefore, becomes a factor 75 of vital importance. It is moreover, highly important that whenever the picker or corresponding machine is stopped for any reason that the delivery of oil should also cease 80 and that when the machine is again started the delivery should again immediately commence so as to obtain an even and uniform mixture of oil with the cotton at all times in predetermined proportions.

The present process as applied to distributing the oil upon raw cotton, and which is also applicable to distributing oil upon other materials, consists in delivering a controllable and accurately regulated quantity 85 of the oil under a predetermined hydrostatic head from a column of oil diverted from a continuously circulating body of oil, the rate of flow of which is correlated to the rate of movement of the material, and the 90 quantity of which is greater than the desired rate of delivery of the oil and preferably discharging the surplus of oil supplied to the column and returning the same to the circulating body thereof.

An illustrative type of apparatus for performing the method above described is illustrated in the accompanying drawings, in which,

5 Fig. 1 is a diagrammatic side elevation of the feeding mechanism for delivering the material to a cotton picker, with the present invention associated therewith;

10 Fig. 2 is a preferred form of spraying device for uniformly distributing the oil, or other liquid, upon the material;

15 Fig. 3 is an enlarged view, mainly in vertical section, of a preferred form of commercial apparatus for delivering and distributing the oil, or other liquid, upon the material;

20 Fig. 4 is a view, mainly in side elevation, of a modified form of oil supplying and distributing means adapted to be constructed of usual commercial piping; and,

Fig. 5 is a front elevation of the construction illustrated in Fig. 4.

The apparatus illustrated herein is particularly designed for distributing oil upon a progressively moving body of cotton, or other textile materials, and while the following description is addressed to this particular apparatus it will be understood that the apparatus is of an illustrative character as disclosing one preferred embodiment of the invention, and that other forms of apparatus, capable of performing the process herein described, may be employed. It will also be understood that the process may be utilized for the treatment of other kinds of material to which the invention is applicable within the broad scope of the invention claimed.

40 The apparatus may be generally described as comprising a feeder for the cotton to a breaker lapper, or other machine, for preliminarily treating the cotton, the oil being applied thereto by means of a spraying device positioned to project the oil upon the cotton, the spraying device being supplied with a regulated quantity of oil, or other liquid, delivered to it under a predetermined hydrostatic head from a column of oil of predetermined height produced by diverting 45 a regulated portion of a circulating body of oil which is circulated at a rate of speed correlated to the rate of movement of the material in the feeder.

55 The construction illustrated in the accompanying drawings comprises a feeder having a hopper 1 provided at its bottom with a travelling endless carrier 2 which constantly forces the material in the hopper against an elevator 3 in the form of an endless apron 60 provided with a toothed surface, such as card clothing or the like, from which the material is discharged by a suitable doffer 4 to the apron 5 of the breaker lapper, or other machine, for giving the cotton its preliminary treatment.

One or more spray heads 6, located above the hopper 1 and directed downwardly at an angle to the direction of movement of the material, serve to project the oil, or other liquid, upon the material carried by the apron 2 at the bottom of the hopper. The spray head or heads 6 are supported from a horizontal pipe 7, which is carried by a bracket 8 secured to the side of the hopper. The preferred form of spray head, which is illustrated in Fig. 2, comprises a casing 9 having an air compartment 10 and a mixing compartment 11. The oil is supplied to the head through a pipe 12 which communicates with a conduit 13 extending axially through the chamber 10 and provided at its outer end with a suitable nozzle 14. Air is forced into the mixing chamber tangentially through ports 15 desirably located in proximity to the tip of the nozzle so that the air under pressure assumes a rotary or whirling motion therein of relatively high velocity which breaks up or pulverizes the particles of oil and discharges it through the outlet 16 of the spraying device. A portion of the air under pressure is permitted to pass through an annular nozzle 17 surrounding the outlet 16 and acts to enclose the whirling vaporized spray in a conical envelope which restricts and condenses the action of the jet and insures a uniform distribution of the spray upon the material.

55 This construction may be and is substantially the same as that disclosed in my prior Patent No. 1,401,376 above identified.

60 Air, preferably under low pressure, is supplied to the air chamber 10 through a pipe 18 leading from a blower 19 which may be mounted and actuated in any suitable manner.

65 Means for supplying oil to the spraying device illustrated in Fig. 3 comprises a pump 20, the inlet 21 of which communicates with a chamber 22 in a hollow metallic base 23 to which oil is supplied through a pipe 24 from a suitable tank 25 which may be located at any convenient position. The vertical location of the tank with respect to the pump should be such that the oil, or other liquid, will always stand at a level somewhat higher than the pump itself, thus providing for the priming of the pump. Each machine to which the oil is to be supplied may be connected to a single main supply tank, although each machine may, if preferable, have its own independent tank or source of supply.

70 The pump desirably is driven by a pulley 26 and belt 27 from a shaft which directly or indirectly drives the carrier 2 and the elevator 3 of the feeder so that the speed of the pump will always be correlated to the speed of movement of the material in the feeder.

75 The liquid is delivered by the pump to

100

110

115

120

125

130

- a riser 28 which desirably is provided with a removable strainer 29 to prevent possible accumulation of lint and other impurities in the pipe leading to the sprayer. The upper 5 end of the riser 28 communicates with a chamber 30 in a header 31. The header 31 is divided by horizontal and vertical partitions 32 and 33 to provide a supplementary chamber 34 which communicates with the 10 upper end of a return pipe 35 of relatively large diameter, the lower end of which communicates with the chamber 22 in the base 23. A stand-pipe 36, preferably located in axial alinement with the return pipe 35, is 15 seated in the header 31 and communicates with the chamber 32 into which the liquid is delivered from the riser. The vertical partition 33 of the header has a port 37 which is controlled by a needle valve 38 20 having a screw threaded stem which engages corresponding complementary screw threads in the wall of the header. The end of the needle valve 38 is provided with a slot to permit adjustment of the valve and 25 desirably a screw threaded plug 39, seated in a countersink beyond the outer end of the needle valve, serves to prevent escape of any oil which may leak along the screw threads of the plug.
- 30 An outlet conduit, desirably in the form of an externally screw threaded pipe 40, is mounted in the partition 33 of the header and is adapted to provide an overflow dam for the column of liquid in the stand-pipe 36 and to discharge the same into the return pipe so that the excessive oil delivered to the 35 column is recirculated through the pump. Desirably a gauge glass 41 is mounted in the header and extends upwardly in 40 parallelism with the stand-pipe so that the height of oil in the stand-pipe may be readily observed. A cap 42 is mounted upon the upper end of the stand-pipe and the gauge glass and is provided with a vent 45 port 43 which communicates with both the stand-pipe and the header.
- The pipe 12, which leads to the spray head or heads 6, preferably communicates with a port 44 leading to the chamber 30 of the 50 header 31 so that the oil or other liquid which is delivered to the spray head or heads is under a constant hydrostatic head which is determined by the height of the adjustable outlet conduit 40 or dam. The 55 spray head tip 14 should be somewhat higher than the port 44 which communicates with the feed pipe 12. As a result of this vertical relation between the level of the column of oil in the stand-pipe, which 60 is determined by adjustment of the outlet pipe 40 and the nozzle, all of the oil or other liquid in the delivery pipe 12 will be discharged backward by siphoning into the chamber 30 of the header and thence through 65 the port 37 into the return pipe 35 as soon as the level of the oil or other liquid in the stand-pipe falls below the tip 14 of the sprayer. Thus the supply of oil will be immediately cut off upon stoppage or substantial diminution in the speed of movement of the conveyer 2 which supports the textile material.
- 70 The starting up and thereafter the continuous operation of the apparatus may be described as follows:—In order to make the preliminary adjustment after the apparatus has been erected the valve 38, which controls the area of the port 37, should at first be opened wide. This port desirably is of such size that when the apparatus is started up with the valve 38 wide open all of the oil delivered by the pump will pass through the port 37 into the return pipe 35 and drawn therefrom by the suction of the pump. Under these conditions the oil or other liquid 80 will not then rise in the stand-pipe 36 as high as the top of the outlet pipe 40 or dam and no liquid will be delivered to the spray heads.
- 85 When the mechanism for forwarding the textile material and the pump which is driven in correlation therewith has reached full speed of operation the valve 38 should be gradually closed until the oil or other liquid rises in the stand-pipe sufficiently to flow 90 over the top of the outlet pipe or dam 40. This pipe may be then gradually adjusted until a hydrostatic head of oil is established which will cause the delivery of oil to the spray heads.
- 95 During these preliminary operations the spray heads should not be supplied with air. As soon as the delivery of oil or other liquid to the spray heads takes place a suitable receptacle may be placed under it to 100 receive the oil, and by measuring the amount of oil delivered by the spray head in a known interval of time the amount of oil which would be sprayed upon the material may be accurately determined. By further 105 adjustment of the outlet pipe or dam 40 an accurate calibration of the device may be obtained which will insure the delivery of exactly the desired quantity of oil to the spray head in a given interval of time. Air 110 may then be supplied to the spray head and the textile material fed into the hopper and the machine continuously operated thereafter.
- 115 It is obvious that the arrangement of the apparatus as a whole is such that a very delicate adjustment of the delivery of oil to the spray head is possible and that when the initial adjustment of the valve 38 and the height of the adjustable dam 40 have 120 once been established the delivery of oil to the spray head will be uniform because the flow of oil through the connection to the spray head and the pipe 12 leading thereto takes place purely by the hydrostatic 125 130

head of oil imposed upon the delivery connection and because the hydrostatic head in turn depends upon the adjustment of the vertical outlet pipe or dam 40. It may be observed that the apparatus may be successfully operated without the presence and use of the visible gauge 41. The visible gauge, however, is a very convenient and desirable accessory since any material change in the level of the oil in the gauge would indicate the probable presence of some obstruction in the system. For example, a fall in the level of the oil in the visible gauge would be most likely to indicate the accumulation of impurities on the screen of the strainer and the necessity of their removal by cleaning. Such cleaning can be conveniently accomplished by shutting down the machine, thus permitting the oil to flow into the return pipe 35, after which the strainer screen may be removed and cleaned in a very brief interval.

The fundamental and novel principle in the present invention is not concerned with the particular type of machinery by means of which the textile materials are processed, nor with the spraying or other means for applying fluid to the material, but lies wholly in the method and means disclosed herein for insuring that the oil or other liquid with which the fibres are to be treated shall be so delivered to the spraying or fluid-applying means that the rate of delivery of the fluid is always under close and accurate control and is continuous when the entire apparatus is in normal operation of processing, but not at other times.

The details of apparatus are subject to wide modification without departure from the scope of the invention. In Figs. 4 and 5, for example, a different form of apparatus is illustrated which is constructed entirely of piping and structural materials which may be obtained in the open market. The construction illustrated in Figs. 4 and 5 comprises a vertical metallic plate 45 which has secured to its lower end an L-shaped metallic base 46, a plate 47 being secured to the side of the hopper frame. The pump 20, preferably of the rotary type, is mounted upon a stand 49 which is secured to the base. A riser 50 from the pump, which may be of usual piping with ordinary connections to the pump, extends vertically and has secured to its upper end a filter 51. The riser pipe has a section 52 which extends upwardly beyond the screen section 51 and is connected to a union 53 from which a branch pipe or by-pass 54 having therein a valve 55 leads to a return pipe 56 of relatively large diameter which extends vertically in parallelism to the riser pipe.

The stand-pipe and return pipe desirably are connected by a horizontal clamp 57 located adjacent to the connection 52 and the

return pipe may be connected by suitable clamps 58 and 59 to the vertical supporting plate 45. The vertical riser also includes another union 60 which is located above the union 53 and has connected to it the pipe 70 leading to the spray head or heads 6. Another branch 61 from the union 60 is connected to an elbow 62 to which is connected a flexible pipe 63 which is connected by a suitable elbow 64 and to a union 65 forming part of a vertical stand-pipe 66 which is slidably mounted in a collar 67 upon the upper end of the return pipe 56 and desirably extends a considerable distance into the return pipe. The stand-pipe 66 may be secured in vertical position by a suitable set screw 68 or other means which will permit its vertical adjustment.

Desirably a gauge glass 69 extends upwardly from the union 60 which forms part of the riser 50. The upper end of the stand-pipe is provided with a vented cap 70 and a similar vented cap 71 is desirably secured to the upper end of the gauge glass.

The operation of this device is in all respects equivalent to that shown in Fig. 3. In order to make the preliminary adjustment after the apparatus has been erected the valve 55 in the by-pass pipe 54 is first opened wide. This by-pass and valve preferably are of such size that when the apparatus is started up with the valve 55 wide open all of the oil or other liquid delivered by the pump will pass through the by-pass into the return pipe 56, the relation being such that the oil will not then rise in the stand-pipe 66 as high as the point where the delivery pipe 12 is connected to the union 60. At this preliminary stage of adjustment the stand-pipe 66 should be in its lowest position of adjustment so that the outlet of the flexible tube or pipe 63 will be at substantially the same level as its inlet.

When the machinery conveying the textile material and the pump, which is driven at a speed correlated thereto, is in operation at full speed the by-pass valve 55 should be gradually closed until oil appears at the lower end of the gauge glass 69, thus indicating that the excess of oil above that which passes through the by-pass is now passing through the flexible tube into the stand-pipe 66. The adjustable stand-pipe 66 may be then gradually raised until a sufficient hydrostatic head of oil or other liquid is established to cause the delivery of oil to the spray heads through the pipe 12.

During these preliminary operations the spray heads are not supplied with air. As soon as the delivery of oil to the spray head takes place a suitable receptacle may be placed under it to receive the oil and by measuring the amount of oil delivered by the spray head in a known interval of time and by gradually adjusting the stand-pipe

66 a position will be eventually reached when the delivery of oil to the spray heads at the desired rate is established. The height of oil in the visible gauge 69 may then be 5 noted for the purpose of establishing that point or position of adjustment at which the desired delivery of oil through the spray head is effected.

From the foregoing description it will be 10 observed that the outlet of the flexible tube is in effect a dam over which the flowing of a small surplus of oil may be continuously maintained while the machine is in operation. The height of the dam, since it establishes 15 the hydrostatic head of oil on the spray head and its delivery connections, is therefore a controlling means which may be adjusted to effect the desired rate of delivery of oil to the spray head. It will also be 20 noted that the delivery of oil to the spray head will immediately cease if the machine is stopped or the speed of the pump materially reduced. This is because the by-pass valve 55, which is always partially open, will permit 25 the immediate escape of oil from the riser, the pipe 12 leading to the spray head, and the flexible tube 63 which leads to the stand-pipe if the rate of discharge of oil from the pump is materially lowered, since 30 only a small surplus of oil is flowing through the flexible pipe 63 and over the dam formed by its connection to the adjustable pipe 66.

It is important that the vertical height of the union 60 and inlet to the feed pipe 12 35 leading from the stand-pipe should be somewhat lower than the tip 14 of the oil nozzle within the spray head 9. As a result of this vertical relationship between the delivery connection and the tip 14 all of the oil in 40 the fluid delivery pipe 12 will be discharged backward by siphoning into the riser pipe as soon as the level of the oil in the riser pipe falls below the connection of the flexible pipe 63 to the stand-pipe. The arrangement 45 of the apparatus is such that a very delicate adjustment of the delivery of oil to the spray head is possible and is also such that when the initial adjustment of the by-pass valve and the height of the adjustable stand-pipe 66 have once been carefully established 50 the delivery of oil to the spray head will be uniform. This is because the flow of oil or other liquid through the connection to the spray head and the pipe 12 leading thereto 55 takes place purely by virtue of the hydrostatic head of oil imposed upon the delivery connection and because the hydrostatic head in turn depends upon the adjustment of the vertical stand-pipe 66 and the dam which is formed by the connection of 60 the flexible pipe 63 to the stand-pipe. The presence of the visible gauge is not absolutely necessary, but, however, is a convenient and desirable accessory for the reasons heretofore specified.

It will, therefore, be observed that the operation of this device is identical in all respects with that of the commercial device illustrated in Figs. 1 and 3 heretofore described and merely differs therefrom in 70 that the latter is formed of commercial structural parts and piping which may be obtained and assembled in the field.

It will be obvious that various other types of construction may be employed to perform 75 the process disclosed herein and within the scope and meaning of the following claims.

Having thus described the invention, what is claimed as new, and desired to be secured by Letters Patent, is:

1. The process of delivering liquid to a liquid-distributing means at a predetermined uniform rate which comprises circulating a confined body of the liquid at a rate of flow greater than the desired rate of delivery 85 thereof, maintaining thereby a column of said liquid of a uniform height and delivering the liquid from said column under a predetermined hydrostatic head and uniformly distributing the liquid thus delivered in the 90 form of a spray.

2. The process of delivering liquid at a predetermined rate to a moving body of material which comprises circulating a confined body of the liquid at a rate of flow 95 correlated to the rate of movement of said material and greater than the desired rate of delivery of said liquid, maintaining thereby a column of said liquid of a uniform height and delivering the liquid to said material from said column under a predetermined hydrostatic head and distributing the liquid thus delivered in the form of a spray uniformly upon said moving body of material.

3. The process of uniformly distributing a controllable amount of liquid upon a moving body of fibrous material which comprises circulating a confined body of the liquid at a rate of flow correlated to the rate of movement of said material and greater than the desired rate of delivery of said liquid, diverting, by controllable restriction of said circulation, a column of said liquid, maintaining said column of liquid at a uniform 110 height, delivering the liquid from said column under a predetermined hydrostatic head and spraying the liquid thus delivered upon the moving material.

4. The process of uniformly distributing 120 a controllable amount of liquid upon a moving body of fibrous material which comprises circulating a confined body of the liquid at a rate of flow correlated to the rate of movement of said material and greater than the desired rate of delivery of said liquid, diverting, by controllable restriction of said circulation, a column of said liquid, maintaining said column of liquid at 125 a uniform height, delivering the liquid from 130

said column under a predetermined hydrostatic head and spraying the liquid thus delivered upon the moving material and arresting the delivery of liquid when the height of the column is decreased, and, when the rate of movement of the material is reduced.

5. The process of delivering a uniform limited supply of liquid to a spraying device for distributing liquid upon a moving body of textile material which comprises circulating a confined body of the liquid at a rate of flow correlated to the rate of movement of said material and greater than the desired rate of delivery of said liquid, diverting, by controllable restriction of said circulation, a portion of the liquid to produce a column of liquid having a definite height and delivering the liquid from said column to said spraying device under only a sufficient hydrostatic head to supply continuously a small amount of liquid to said spraying device.

6. The process of delivering a uniform limited supply of liquid to a spraying device for distributing liquid upon a moving body of textile material which comprises circulating a confined body of the liquid at a rate of flow correlated to the rate of movement of said material and greater than the desired rate of delivery of said liquid, diverting, by controllable restriction of said circulation, a portion of the liquid to produce a column of liquid having a definite height, maintaining the column of liquid at said definite height by discharging the surplus of liquid supplied to the column and delivering the liquid from said column to said spraying device under only a sufficient hydrostatic head to supply continuously a small amount of liquid to said spraying device.

7. Apparatus for uniformly delivering a regulated quantity of liquid to a travelling body of material comprising means for continuously moving the material at a substantially uniform rate of speed, spraying heads arranged to distribute the liquid uniformly upon said travelling body of material, means for circulating the liquid at a rate correlated to the speed of movement of the material, means for delivering a portion of the circulating liquid to said spraying means and means for maintaining a predetermined hydrostatic head upon the liquid-delivering means.

8. Apparatus for uniformly delivering a regulated quantity of liquid to a travelling body of material comprising means for continuously moving the material at a substantially uniform rate of speed, spraying heads arranged to distribute the liquid uniformly upon said travelling body of material, means for circulating the liquid at a rate correlated to the speed of movement of the

material, means for delivering a portion of the circulating liquid to said spraying means and means for maintaining a predetermined hydrostatic head upon the liquid-delivering means operable upon substantial diminution of the rate of movement of said material or stoppage thereof immediately to stop the delivery of liquid.

9. Apparatus for uniformly delivering a regulated quantity of liquid to a travelling body of material comprising means for continuously moving the material at a substantially uniform rate of speed, spraying heads arranged to distribute the liquid uniformly upon said travelling body of material, means for circulating the liquid at a rate correlated to the speed of movement of the material, controllable means for producing from said circulating liquid a column of liquid having a predetermined height and means for delivering a portion of the liquid from said column of liquid under a predetermined hydrostatic head to said spraying heads.

10. Apparatus for uniformly delivering a regulated quantity of liquid to a travelling body of material comprising means for continuously moving the material at a substantially uniform rate of speed, spraying heads arranged to distribute the liquid uniformly upon said travelling body of material, means for circulating the liquid at a rate correlated to the speed of movement of the material, controllable means for producing from said circulating liquid a column of liquid having a predetermined height, means for delivering a portion of the liquid from said column of liquid under a predetermined hydrostatic head to said spraying heads, and means for regulating the height of said column whereby the hydrostatic head upon the liquid-delivering means may be varied.

11. Apparatus for delivering liquid to a liquid-distributing means at a predetermined rate of flow comprising a conduit, means for continuously circulating the liquid therethrough at a uniform rate of flow greater than the desired rate of delivery of said liquid, a stand-pipe communicating with said conduit, controllable means for maintaining a column of liquid of predetermined height in said stand-pipe and means for delivering the liquid from said stand-pipe to said liquid-distributing means under a predetermined hydrostatic head.

12. Apparatus for delivering liquid to a liquid-distributing means at a predetermined rate of flow comprising a conduit, means for continuously circulating the liquid therethrough at a uniform rate of flow greater than the desired rate of delivery of said liquid, a stand-pipe communicating with said conduit, an adjustable valve in said conduit operable to control the flow of liquid into said stand-pipe, means for preventing the liquid column in said stand-pipe from ex-

- ceeding a predetermined height and means for delivering liquid from, said stand-pipe to said liquid-distributing means under a predetermined hydrostatic head.
- 5 13. Apparatus for delivering liquid to a liquid-distributing means at a predetermined rate of flow comprising a conduit, means for continuously circulating the liquid therethrough at a uniform rate of flow greater than the desired rate of delivery of said liquid, a stand-pipe communicating with said conduit, an adjustable valve in said conduit operable to control the flow of liquid into said stand-pipe, an outlet conduit communicating with said stand-pipe operable to prevent the liquid column in said pipe from exceeding a predetermined height and means for delivering the liquid from said stand-pipe to said liquid-distributing means under a predetermined hydrostatic head.
14. Apparatus for delivering liquid to a liquid-distributing means at a predetermined rate of flow comprising a conduit, means for continuously circulating the liquid therethrough at a uniform rate of flow greater than the desired rate of delivery of said liquid, a stand-pipe communicating with said conduit, an outlet conduit, of smaller diameter than said stand-pipe mounted within said stand-pipe and adjustable longitudinally thereof, forming a dam and acting to maintain the column of liquid in said stand-pipe at a predetermined height and means for delivering the liquid from said stand-pipe to said liquid-distributing means under a predetermined hydrostatic head.
15. Apparatus for uniformly delivering liquid upon a moving body of fibrous material comprising a travelling conveyer for the material, spraying means positioned to distribute the liquid upon the material on said conveyer, means for supplying liquid to said spray head comprising an endless conduit for the liquid, a stand-pipe extending upwardly therefrom and communicating therewith, a pump in said conduit, means for driving said pump at a speed correlated to the speed of movement of said material, adjustable means for restricting the flow of liquid in said conduit to maintain a column of liquid in said stand-pipe at a substantially predetermined height, an outlet for the liquid in said stand-pipe for preventing the liquid column to exceed a predetermined height and a delivery conduit leading to said spraying means communicating with said stand-pipe, whereby the liquid will be supplied to the spraying means at a predetermined hydrostatic head.
16. Apparatus for uniformly delivering liquid upon a moving body of fibrous material comprising a travelling conveyer for the material, spraying means positioned to distribute the liquid upon the material on said conveyer, means for supplying liquid
- to said spray head comprising an endless conduit for the liquid, a stand-pipe extending upwardly therefrom and communicating therewith, a pump in said conduit, means for driving said pump at a speed correlated to the speed of movement of said material, adjustable means for restricting the flow of liquid in said conduit to maintain a column of liquid in said stand-pipe at a substantially predetermined height, an outlet conduit forming a dam communicating with said stand-pipe acting to maintain the liquid column in said pipe at a predetermined height relatively to the height of said spraying means and a delivery conduit leading to said spray head under a predetermined hydrostatic head.
17. Apparatus for uniformly delivering a limited quantity of liquid upon a moving body of fibrous material comprising a travelling endless conveyer for the material, spraying means positioned to distribute the liquid upon the material on said conveyer, a pump for the liquid, means for driving said pump at a speed correlated to the rate of movement of said material, a riser leading from said pump and a return conduit communicating with the intake of said pump, a stand-pipe communicating with said riser, means for regulating the flow of liquid from said riser into said return pipe operable to maintain a column of substantially predetermined height in said stand-pipe, an outlet conduit forming a dam communicating with said stand-pipe acting to maintain the liquid column in said stand-pipe at a predetermined height relatively to the height of said spraying means and a delivery conduit leading from said spray head communicating with said stand-pipe below said dam, whereby the liquid will be delivered to said spray head under a predetermined hydrostatic head.
18. Apparatus for uniformly delivering a limited quantity of liquid upon a moving body of fibrous material comprising a travelling endless conveyer for the material, spraying means positioned to distribute the liquid upon the material on said conveyer, a pump for the liquid, means for driving said pump at a speed correlated to the rate of movement of said material, a riser leading from said pump and a return conduit of larger diameter than said riser communicating with the intake of said pump, a stand-pipe communicating with said riser, located in axial alinement with said return pipe, means for regulating the flow of liquid from said riser into said return pipe to maintain a column of liquid of predetermined height in said stand-pipe, an outlet conduit of smaller diameter than said stand-pipe, located concentrically within said stand-pipe,

and adjustably mounted therein, and communicating with said return pipe and forming a dam acting to maintain the liquid column in said pipe at a predetermined height relatively to the height of said spraying means and a delivery conduit leading to said spraying means communicating with

said stand-pipe below said dam, whereby the liquid will be delivered to said spraying means under a predetermined hydrostatic ¹⁰ head.

In testimony whereof, I have signed my name to this specification.

ALBERT W. THOMPSON.
